CIRCUIT INTERRUPTER

Herbert L. Rawlins, Wilkinsburg, and James M. Wallace, North Braddock, Pa., assignors to Westinghouse Electric & Manufacturing Company, East Pittsburgh, Pa., a corporation of Pennsylvania

Application July 19, 1940, Serial No. 346,300

49 Claims. (Cl. 200—116)

Our invention relates generally to electric circuit interrupting means, and more specifically to a novel circuit breaker construction which is capable of automatically reclosing the circuit in response to a circuit interrupting operation.

Our invention relates, in general, to the type of circuit breaker having separable contacts normally biased closed, with current responsive means for separating said contacts sufficiently to draw an arc and having means whereby the pressure generated by said arc is utilized to fully open the contacts. Time delay means is provided to oppose the action of said biasing means in closing the breaker contacts, and to be responsive to a predetermined number of closely succeeding reclosures to lock the contacts open. This general type of breaker is disclosed and claimed in the copending application of J. M. Wallace for "Circuit interrupter," Serial No. 345,051, filed July 12, 1940, and assigned to the Westinghouse Electric & Manufacturing Company, the assignee of this application.

Our invention, while embodying some of the general features of said copending application, is specifically directed to an improved and simplified construction of a circuit breaker of this general type.

One object of our invention is to provide a novel circuit breaker construction of the type described, which is of a relatively simple and compact construction.

Another object of our invention is to provide in a circuit interrupter having separable contacts located in a substantially closed arc chamber, novel means for flushing said chamber of arc gases and introducing therein a fresh supply of an arc-extinguishing medium in response to each interrupting operation thereof.

Another object of our invention is to provide in a circuit breaker which automatically recloses the contacts thereof in response to a circuit interrupting operation, novel means for delaying the reclosure of said contacts a predetermined time after the preceding interrupting operation.

Another object of our invention is to provide novel lockout means for an automatically reclosing circuit breaker, which means is responsive to a predetermined number of closely successive reclosures of said breaker to lock the breaker contacts in an open position.

Another object of our invention is to provide in an automatically reclosing circuit breaker, novel combined time delay means for the reclosing operation, and lockout means for locking the breaker contacts open in response to a prede-

termined number of successive reclosures thereof.

Another object of our invention is to provide novel current responsive tripping means for a circuit breaker.

5 Another object of our invention is to provide in a circuit breaker of the type described, current responsive tripping means for a circuit breaker which is operable in response to the passage therethrough of currents above a predetermined value to positively move at least one of the breaker interrupting contacts out of engagement with the other of said breaker contacts.

A further object of our invention is to provide a circuit breaker having separable contacts immersed in an arc-extinguishing liquid, with novel indicating means for indicating the quantity of liquid in the breaker.

A still further object of our invention is to provide a novel arrangement of parts of a circuit breaker of the type described, and wherein the separable contacts thereof are immersed in an arc-extinguishing liquid.

These and other objects of our invention will become more apparent upon consideration of the following detailed description of a preferred embodiment thereof, taken in connection with the attached drawings, in which:

Figure 1 is a substantially central longitudinal cross-sectional view through a circuit breaker embodying our invention;

Fig. 2 is a view similar to Fig. 1, but taken at right angles to the plane of Fig. 1;

Fig. 3 is a view like Fig. 1 but showing the operating parts of the circuit breaker in an open position;

Fig. 4 is a top plan view of the circuit breaker shown in Figs. 1, 2 and 3 with the outer cover removed; and

Fig. 5 is a side elevational view of the upper end of the circuit breaker shown in Figs. 1 to 4, with the outer cover in section.

Referring to the drawings, the circuit breaker illustrated therein is shown as being contained in an insulating tubular casing 2 which may be of any desired insulating material, such for example, as porcelain, glass, or the like. The casing 2, as shown in Fig. 1, has a closed bottom end portion and an open top. The open top is provided with an upper terminal cover assembly 4, and the closed bottom of the casing is provided with a lower terminal assembly 6. An intermediate portion on the casing has a substantially cylindrical wall portion 8 upon which is mounted a cushioning sleeve 10 of rubber, fiber, or the like, and on opposite sides of which may be clamped

supporting brackets 12, as by bolts 14. The outer end of each bracket 12 may be turned laterally as at 17, and apertured as at 16, for the reception of a bolt for securing the brackets in position on a pole or other supporting structure.

The lower terminal assembly 6 is mounted at the closed bottom portion of the insulating casing 2 by means of a bolt 18 extending through an aperture 19 in the closed end of the casing 2, and the bolt is provided with an enlarged disc-like head portion 20 positioned within the casing 2, with packing material 22 interposed between the head 20 and the adjacent inner surface of the closed end of insulating casing 2. The packing material 22 may be of any desired packing material, preferably one resistant to oil, such for example, as cork, fiber, or synthetic rubber. Bolt 18 has a bore 15 therethrough, the outer end of which is closed by a threaded plug 21 for the purpose of draining casing 2 when desired. The bolt 18 is secured in position by a nut 24 drawn up on the bolt against a washer 26 positioned between the nut 24 and the outer wall of the closed end of the casing 2. A terminal strap 28 may be also secured to the bolt 18 as by means of a second nut 30, for supporting terminal sockets 29 having one side thereof secured in notches in a downwardly extending portion of strap 28, with clamping screws 31 threadedly engaged in apertures in the socket walls for securing a conductor therein.

The upper terminal assembly 4 is in the form of a cover for the open end of the casing 2, which not only acts as a cap or cover for the casing, but, as will be hereinafter more fully explained, acts as a support for the interrupter and its operating mechanism when in operative position within the casing 2. Referring to Figs. 1 and 2, it will be noted that the cover 32 is provided with a transversely extending relatively narrow hollow portion for the reception of certain parts of the circuit breaker operating mechanism, and the top wall of which is provided with an aperture for the reception of a screw threaded filler plug 34, so that the supply of arc-extinguishing fluid within the casing 2 may be renewed when necessary. The cover 32 includes a peripheral flange portion 36 adapted to seat on the upper end walls of casing 2, and this flange has at its outer edge a downwardly turned lip portion 38 for properly positioning the cover on the open end of the casing 2. Packing material 40 is interposed between the cover and the open end of the casing similar to the packing material 22, and the cover 32 is secured to the casing 2 by means of a support 42 fixedly mounted on the outside of the casing 2. The support 42 is in the form of an annulus which is substantially channel-shaped in cross-section, with the channel facing the outer surface of casing 2. The annular support 42 is secured to the casing by cast metal or the like 44, which is poured in between the support 42 and the outer casing wall so as to enter within the channel of the support 42 and between corrugations 46 provided on the outer surface of the casing to securely anchor the support 42 thereto. We provide a plurality of laterally extending ears 52 and 50 on the support 42 and cover flange 36, respectively, which ears are apertured for the reception of bolts 48 for securing the cover to the supporting flange 42 and, therefore, to the insulating casing 2.

The insulating casing 2 may be of any desired shape and cross-section, preferably circular, as shown, so that the hollow portion of the cover 75

32 described above extends substantially diametrically of the casing, and so that segmental portions of cover flange 36 extend inwardly over the open end of the casing as shown at 54 in Fig.

5 5. Secured to these segmental portions of the cover flange 36 are spaced supporting plates 56 having angularly bent ends insulatingly secured to the segments 54 of cover flange 36, by machine screws 51, with interposed insulating washers 58, 10 and insulating bushings 60. The insulating washers 58 and bushings 60 may be of any desired insulating material such as fiber, or a synthetic resin material. As shown, the supporting plates 56 extend substantially in parallel relation downwardly in the tubular insulating casing 2, and one function of these plates is to support a tubular interrupter housing 62. The interrupter housing 62, as shown, is substantially circular in cross-section, although it is obvious that any other desired cross-section may be employed if desirable, and it includes an insulating tubular section 64 which may be of any desired insulating material, such as fiber or the like. Opposite ends of the insulating tubular section 64 are screw threaded, and one end is threaded into an end of a metallic tubular section 66 to form the housing 62. A lower end cap 68 is threadedly engaged with the lower end of the insulating tubular section 64, and an upper end cap 70 is threaded into the upper end of the metallic tubular section 66. As shown, the supporting plates 56 are secured to the tubular housing 62 by screws 72, engaging the upper end cap 70. The lower end cap 68 is reduced in section to provide a shoulder against which the upper end 35 of a coil compression contact spring 74 is seated, to be compressed against the enlarged head 20 of bolt 18 of the lower terminal assembly 6. Spring 74 may be of any desired resilient conducting material, such as a copper alloy.

40 A substantially central bore is provided through the lower end cap 68 which includes an upper threaded portion 76, an intermediate cylindrical portion 78 and an outer bore 80 of reduced area. A flanged bushing 82 is threaded into the upper portion 76 of the bore through the lower end cap 68, and this bushing is preferably of material capable of withstanding arcing, such for example as a tungsten alloy. The flanged bushing 82 is itself provided with a bore as shown. Slidably mounted in the cylindrical portion 78 of the lower end cap bore is a valve disc 84 resiliently urged into engagement over the lower end of the bore through the flanged bushing 82, by a coil compression spring 86 seated between the valve disc 84 and the shoulder provided at the lower end of the cylindrical bore portion 76. This valve arrangement acts as a pressure relief means for the tubular insulating member 64, and the strength of spring 86 is chosen so as to permit the valve disc to open the passage through the lower end cap in response to predetermined pressures in insulating tube 64, to prevent damage thereto.

65 A substantially circular groove 88 is cut in the upper surface of end cap 68 opening into the tubular insulating member 64, and having radial vent passages 90 extending outwardly to communicate the interior of the insulating tube 64 with the interior of casing 2. The circular groove 88 is controlled by a substantially annular valve disc 92 which is freely movably mounted between the upper surface of end cap 68 and the adjacent end of insulating tube 64.

70 A hollow contact rod 96 is provided with a lon-

itudinally extending central bore and with an arcing cap 88 threadedly engaged over the lower end thereof, so that in the closed position of the contact, the cap 88 engages the flanged bushing 82, which forms a stationary contact. The arcing cap 88 of the movable contact rod is provided with an aperture 100 to communicate the interior of insulating tube 64 with the interior of the hollow contact rod 96. The movable contact rod 96 extends through an aperture in a closure disc 94 for the upper end of insulating tube 64 in slidable relation therewith. As shown, the closure disc 94 is threadedly engaged in the metallic tube 66 to be tightly engaged with the upper end of insulating tube 64, and the aperture through the closure disc 94 is of a size to closely fit arcing rod 96, so as to prevent leakage of pressure from insulating tube 64 at this point. Obviously, insulating tube 64, end cap 88 and closure disc 94 together form a substantially closed arc chamber 63. Adjacent the lower end of movable contact rod 96 the bore in said rod is enlarged to form a shoulder 102 therein, on which is seated a partition disc 104 maintained in position to close off the bore through the contact rod by a coil compression spring 106, having the opposite ends thereof in engagement with the disc 104 and with the arcing cap 88, respectively. Below the partition disc 104 in the movable contact rod 96 there are provided vent apertures 108, extending through the side walls of hollow contact rod 96 for a purpose to be described.

In the operation of the parts of our novel circuit breaker thus far described, it will be noted that we have provided a substantially closed arc chamber 63. Thus when the movable contact rod 96 is moved upwardly in response to currents in excess of a predetermined value in the circuit, an arc will be drawn between the arcing cap 88 on the contact rod and the flanged bushing 82. Inasmuch as the arcing chamber is disposed well below the level of arc-extinguishing liquid L maintained in the casing 2, it will be substantially filled with such liquid and the arc formed will produce gases under pressure, due principally to decomposition of the arc-extinguishing fluid, and this pressure developed within the arc chamber will move the movable contact rod 96 a further distance away from the stationary contact and out of the arc chamber in a piston-like manner.

The pressure in arc chamber 63 will obviously maintain valve disc 92 seated on groove 88, thereby closing off vent passages 90. In the event the current interrupted is of a relatively high value on the order of short-circuit currents, the pressure within the arc chamber may become dangerously high, and in this event, the pressure will be high enough to move the valve disc 92 downwardly against the bias of coil spring 86 to vent the lower end of the arc chamber to the casing 2. At the same time, referring to Fig. 3, it will be noted that when the moving contact 88 has obtained its fully separated position with respect to the fixed contact bushing 82, the vent apertures 108 will be positioned above closure disc 94 so that the upper end of the arc chamber may then vent through the moving contact rod into the metallic tubular member 66 and thence to casing 2. The arc formed upon separation of the contacts will have been extinguished by the time the movable contact reached the position shown in Fig. 3 and inasmuch as the upper end of the arc chamber is then vented to the casing 2, the pressure of the arc-extinguishing liquid, 75

due to the head of this liquid in casing 2, will unseat annular valve disc 92 to move the same upwardly and permit flow of arc-extinguishing liquid through radial passages 90 and into the lower end of the arc chamber. This action will occur following each circuit interrupting operation of the contacts of our circuit breaker, and thereby permit flushing out of the arc chamber and replacing the used oil therein with fresh oil from the reservoir maintained in casing 2 in response to each interrupting operation of the breaker.

Time delay means for reclosing the movable contact 88, and lockout means for maintaining the movable contact 96 in an upper or open position in response to a predetermined number of closely successive interrupting operations of the breaker, will now be described. The metallic tube 66 is provided with a smooth intermediate cylindrical inner wall 110 for receiving a substantially annular dashpot piston 112 between the tubular member 66 and the movable contact rod 96. As shown, the dashpot piston 112 includes an elongated sleeve portion 114 and an enlarged upper head portion providing a shoulder 116 between the head and sleeve portions, which is adapted to engage an annular cylinder head 118 threadedly engaged in tubular member 66, and provided with an aperture 122 for receiving the sleeve portion of the dash pot piston. A coil compression spring 120 is provided between a shoulder on the head portion of the dashpot piston and the cylinder head 118, to normally maintain the dashpot piston 112 in its uppermost position against upper end cap 70, as shown in the drawings. Shoulder 116 on piston 112 engages head 118 to limit downward movement of the piston and prevent deformation of the relatively light spring 120 which is of a size to be contained in the space between the top flange of piston 112 and head 118 in the lowermost position of the piston, without going soMd.

The aperture 122 through the lower cylinder head 118, is preferably made to provide a slight clearance between the cylinder head and the sleeve portion 114 of the dashpot piston, which is sufficient to permit the escape of arc-extinguishing liquid trapped between the piston 112 and the cylindrical wall 110 of the tubular portion 66. This clearance should be designed to permit movement of the dashpot piston only at a predetermined slow rate. As shown, the upper end of the bore through the dashpot piston 112 is provided with a series of annular notches 124 for a purpose to be hereafter described.

The upper end of movable contact rod 96 is provided with a pair of diametrically opposite slots 126 so that a pawl lever 130 may be pivotally supported on a pivot pin 128 for movement on said pin through the slots 126 in the movable contact rod. A coil spring 132 is provided about the pivot pin 128 and has its ends engaged with the pawl lever 130 and movable contact rod 96, respectively, so as to continually exert a bias on the pawl lever tending to move it in a clockwise direction about its pivot pin 128. The pawl lever 130 has an upper edge inclined as at 134, and a lower pointed edge 136 formed by the lower end thereof being provided at an acute angle to one side edge. The upper end cap 70 for the tubular housing is provided with an enlarged chamber portion 138 intermediate a pair of spaced apertures therein for slidably guiding the movable contact rod 96, and for a purpose hereinafter to be described.

The upper end of movable contact rod 96 is pivotally connected as by pivot pin 140, with one end of an insulating link 142. The link 142 may be of any desired insulating material, such for example, as fiber or a synthetic resin. The opposite end of link 142 is pivotally connected by a pivot pin 144 with an operating lever 146, which in turn is provided with a square aperture mounted on a shaft 148 which is square in cross-section so as to be drivingly connected therewith. The operating shaft 148 has reduced opposite ends thereof journaled in opposite sides of the cover hollow portion, with one end of the shaft extending through one wall of said hollow portion, to have secured thereto an operating handle 150, having an angularly extending end portion 152 adapted to be engaged by manual operating means, such for example, as a hook stick or the like. Within the hollow portion of cover 32, the operating shaft 148 is provided with a cylindrical sleeve 154 freely mounted thereon, and on which is supported a pair of coil springs 156, corresponding ends of which, 158 and 160, are engaged, respectively, with a portion of cover 32 and operating lever 146. The coil springs 156 thereby operate to continually bias operating lever 146 in a clockwise direction, and therefore, to bias movable contact rod 96 into engagement with the fixed contact bushing 82. It will be noted that the aperture through which shaft 148 extends is large enough to permit the shaft to be inserted therethrough, and that sleeve 154 in cooperation with a nut 155 prevents withdrawal of the shaft.

In the operation of the time delay contact closing means and lockout means described above; when the movable contact 96 is moved upwardly to interrupt the circuit through the breaker by forming an arc within insulating tube 64, which creates pressure to move the contact upwardly, as previously described, such movement of contact rod 96 operates to stress coil springs 156. When the contact 96 attains its uppermost position, as shown in Fig. 3, the pawl lever 130 has its upper end positioned in the enlarged chamber 138 formed in the upper end cap 70 of tubular housing 62, so that it may move in a clockwise direction about its pivot 128 under the influence of coil spring 132 sufficiently, so that the point 136 thereof will be urged into the lower notch 124 of dashpot piston 112. Thus when the arc has been extinguished within arc chamber 63, the movable contact 96 is free to move downwardly under the influence of coil springs 156. This downward movement with pawl lever 130 engaged with the lower notch 124 on the dashpot piston, causes the dashpot piston to be carried down with the movable contact rod a predetermined distance until engagement of the upper end of pawl lever 130 with the lower aperture 131 in upper end cap 70 causes the pawl lever to be rotated in a counter-clockwise direction about its pivot to remove the point 136 thereof from the lower notch 124 on the dashpot piston 112. The resistance of the dashpot piston to movement is thereby removed from the contact rod 96, and the coil springs 156 can then move contact rod 96 into full engagement with the fixed contact bushing 82 with an accelerated movement or snap action. If the fault which caused opening of the breaker has been cleared when the breaker recloses, the dashpot piston 112 moves slowly up to its normal position shown in Figs. 1 and 3 of the drawings, under the bias exerted by coil spring 120. However, if the overload is still present in the circuit when the contacts are reclosed, the breaker will

be tripped substantially instantaneously to re-open the contacts in the manner previously described, and the movable contact rod will move upwardly until the arc is extinguished in the arc chamber, and will then be moved back downwardly in the same manner described above. This time, however, the point 136 of pawl lever 130 will engage in the second notch 124 of dashpot piston 112, because on a closely succeeding 10 interrupting operation of the circuit breaker, the dashpot piston 112 will not have had time to reach its normal upper position shown in the drawings, but will be somewhat below this position, so that the pawl lever can engage the next 15 succeeding higher notch on the dashpot piston. The contact rod 96 will thereupon move downwardly to engage the fixed contact bushing 82 and the dashpot piston 112 will be moved a greater distance downwardly along the cylindrical inner wall 110 in tubular member 66.

Upon this reclosure, if the fault still has not been cleared from the circuit, the contact rod 96 will again be moved upwardly substantially instantaneously and will again be reclosed as before, only this time the point 136 of pawl lever 130 will engage the upper notch 124 on dashpot piston 112, and upon reclosing the contacts, the dashpot piston will be moved a still further distance downwardly in tubular member 66. If the 25 fault continues on the circuit after this third reclosure, the contacts will again be opened, and this time the point 136 of pawl lever 130 will engage the top of dashpot piston 112 and move the shoulder 116 of the piston into engagement with 30 the cylinder head 118 before the pawl lever engages the edge of aperture 131 to move it in a counter-clockwise direction out of engagement with dashpot piston 112. This will obviously 35 prevent reclosure of movable contact rod 96 and 40 fixed contact bushing 82.

It can, therefore, be seen that upon the occurrence of a continuing fault in a circuit, our circuit breaker operates to automatically reclose the circuit a predetermined number of times (three times in the embodiment illustrated) and then operates to lock the contacts in open circuit position. However, if the circuit is cleared after the first, second or third reclosure, the dashpot piston 112 is permitted to assume its 45 normal position shown in Figs. 1 to 3, so that the breaker may operate upon the occurrence of a continuing fault at a later time, with the same predetermined number of reclosures prior to locking the contacts in an open position.

In the upper part of casing 2, we have provided 50 novel tripping means responsive to currents passing through the breaker above a predetermined value for opening the breaker contacts sufficiently to draw an arc in the arcing chamber, so that the pressure developed by the arc may be utilized to completely and further separate the breaker contacts as heretofore described. This 55 tripping means includes a hook-shaped trip lever 162 which is pivotally mounted adjacent the end of the hook on a pivot pin 164, mounted on the supporting plates 56 for tubular housing 62. A coil spring 166 is provided about the pivot pin 164 and has one end 168 thereof engaged with an extension 170 of the tip of said hook-shaped trip lever 162, and the other end 171 thereof is engaged with the top of end cap 70 so as to continuously bias trip lever 162 for movement in a counter-clockwise direction about its pivot pin 164.

As shown, the pivot pin 140 pivotally connects

ing the upper end of movable contact rod 96 with link 142, is positioned to overlie the bight portion of lever 162 and lever 162 extends through the slots 126 of contact rod 96 so as to be centrally positioned with respect thereto. Obviously, movement of trip lever 162 under the influence of spring 166, will operate to engage pivot pin 140 and raise contact rod 96 a slight distance away from fixed contact bushing 82 until the extension 170 of trip lever 162 engages the side of end cap 70. Further movement of contact rod 96 in an upward direction by the pressure developed in the arc in the arc chamber is free of trip lever 162.

The upper end of trip lever 162 has secured thereto a catch portion 172 secured to the trip lever between insulating plates 174, as for example, by a rivet 176. The upper projecting end of catch 172 is curved laterally so as to present an edge portion for engagement with a latching means. A bimetallic strip 178 has one end thereof secured to flange 36 of the cover 32, and the other end thereof extends across the top of casing 2 and is provided with an adjustable latch member 182, which is adjustable by virtue of being threadedly engaged through the free end of the bimetallic strip 178. The bimetallic strip is secured to flange 36 in any desired manner, such for example, as by screws 180, and the strip may be constructed in a manner well known in the art, of a pair of laminations comprising materials having different coefficients of expansion rigidly secured together, with, in the present instance, the upper lamination being of a material such as steel, having a relatively low coefficient of expansion, and the lower lamination being of a material such as brass, having a relatively high coefficient of expansion, so that when the bimetallic strip is heated, the outer end thereof will deflect upwardly to bring the latch portion 182 thereof up out of the path of movement of catch 172 on trip lever 162 when moved by coil spring 166.

A flexible shunt 184 electrically connects the outer end of bimetallic strip 178 with the upper end of movable contact rod 96, and movable contact rod 96 is provided with a splasher member 186 secured to the upper end thereof in any desired manner, such for example, as by welding or the like. As shown, the splasher member 186 extends generally outwardly and upwardly from the movable contact rod below bimetallic strip 178, so as to throw oil onto the bimetallic strip when the contact rod moves upwardly to interrupt the circuit, and thereby to aid in cooling the strip to hasten its return back to its normal position shown in Figs. 1, 2 and 3.

On top of casing cover 32 and at one side thereof, we provide an angle piece 188, one leg of which is secured to the flange 36 of the cover 32 as by screws 190, and the other leg of which has secured thereto a conductor socket 192 provided with a clamping screw 194 for clamping a conductor within the socket.

The electrical circuit through our circuit breaker may now be traced from conductor socket 192 on cover 32, through cover 32, bimetallic strip 178, flexible shunt 184, movable contact rod 96, fixed contact bushing 82, lower end cap 68, conducting spring 74, bolt 18 of the lower terminal assembly, and terminal strip 28 to terminal sockets 29. It can thereby be seen that the bimetallic strip 178 is connected in series in the circuit so as to be responsive to currents above a predetermined

value passed therethrough to deflect in an upward direction.

Upon the occurrence of an overload in the circuit, bimetallic strip 178 will be deflected upwardly, which will remove the latch portion 182 thereof from the path of movement of catch 172 on trip lever 162, allowing this lever to rotate in a counter-clockwise direction due to the influence of coil spring 166. This rotation of trip lever 162 lifts the movable contact rod 96 by engagement of pivot pin 140 a slight amount sufficient to establish an arc between the movable contact rod and the fixed contact bushing 82. This lift need not be very great, and in practice, it has been found that a separation of approximately $\frac{1}{4}$ " is satisfactory. This separation of the circuit breaker contacts causes pressure to be built up in the arc chamber as previously described, and causes further separation of movable contact 96 from fixed contact bushing 82 in an upward direction. In driving upwardly, pivot pin 140 will engage the curved edge 163 of trip lever 162 to reset the trip lever in its normal position shown in Fig. 1. The curved surface 163 of the trip lever acts as a cam surface to move the trip lever in a clockwise direction from its tripped position to a position where the catch 172 thereof may be re-engaged by latch 182 on the bimetallic strip. It will be noted that the upper end of the trip lever 162 is formed with a substantially straight edge 185 of considerable extent so that when the movable contact rod 96 is in its upper position, shown in Fig. 3, it will maintain the trip lever 162 in the position where its catch 172 may be re-engaged by latch 182 for a considerable travel of contact rod 96 adjacent its fully open position. In other words, the trip lever 162 is maintained in a resetting position for a predetermined time (the time required for pivot pin 140 to travel along the straight edge 185 of the trip lever), before the circuit breaker contacts are reclosed. Cooling of the bimetallic strip 178 to its normal position is hastened, of course, by the splashing of liquid from container 2 thereover, by splasher member 186 when the movable contact rod 96 moves upwardly to open the circuit. When the trip lever 162 is reset in the position shown in Figs. 1, 2 and 3, the contact rod 96 then moves downwardly, following, of course, venting and flushing of the arc chamber, as previously described, and carrying with it for a predetermined distance, dashpot piston 112, all as above described. If the overload is still present in the circuit, bimetallic strip 178 will again deflect in the same manner as it did the first time to again cause trip lever 162 to separate the breaker contacts and permit the movable contact 96 to open the circuit and reclose as before. This will continue until the overload either clears, or after a predetermined number of reclosures, the movable contact 96 is locked by the dashpot piston 112 in an open circuit position.

We prefer to provide an outer cover 196 over the hollow portion of cover 32, to normally conceal the operating handle 152 and protect it from the elements when the breaker is mounted in an exposed location. The cover 196 is inverted over the hollow portion of cover 32 and is provided with top and side and end walls, and is pivoted at one corner thereof on a pivot pin 198 to the cover 32. Obviously, when it is desired to refill the breaker, or when access is desired to the operating mechanism, outer cover 196 may be pivotally moved in a clockwise direction, as

seen in Fig. 1, about its pivot 198, so that end wall 200 thereof rests upon flange 36 and the cover 196 will be self-sustaining in this position.

When the breaker contacts are closed, operating handle extension 152 will be positioned in outer cover 196 and will not be visible from the exterior of the breaker (Fig. 1). However, when the breaker is in an open position, especially when the contacts thereof have been locked open by the lockout means previously described, extension 152 of the operating handle will be at least partially positioned below outer cover 196, as is apparent from Fig. 3. This will provide a readily visible indication as to whether or not the circuit breaker is locked open, so that if it is desired to reinsert the breaker in the circuit, it is merely necessary to engage the extension 152 of the operating handle with a hook stick or the like, and pull downwardly thereon to slightly raise movable contact 96. This will release pawl lever 130 from notches 124 on the dashpot piston 112 and permit the piston to move upwardly, and as soon as the piston has moved upwardly a distance corresponding to the distance between adjacent notches 124, the operating handle may be released and the circuit breaker contacts will be closed by springs 156 in a manner described above.

Referring to Figs. 4 and 5, it will be apparent that the hollow portion of casing cap 32 is provided on one side thereof adjacent one end, with a reentrant portion 202 having a top wall 204 overhanging this reentrant portion. This is for the purpose of mounting between the top of cover 32 and overhanging wall 204 a tubular sight glass 206, within which is adapted to move the upper end of a float rod 208, which has connected to the lower end thereof, a float 210 for indicating the level of arc-extinguishing liquid within casing 2.

Also mounted on the same side of the hollow portion of casing cover 32, we provide a manually operable lock lever 212 for locking the circuit breaker contacts in an open position. As shown, this lever 212 is freely pivoted on a pivot pin 214 mounted on cap 32 so as to be movable into engagement with a shoulder 213 provided on operating lever 150 when the lever is in its lowermost position corresponding to the upper position of movable contact rod 96, and, therefore, the open position of the circuit breaker contacts. This lever may be manually moved away from shoulder 213 on operating lever 150, and is normally adapted to be positioned resting on integral supporting means 216 extending laterally outwardly from the adjacent side of the hollow portion of cap 32. Such a manually operable lockout means is desirable in the event it is desired to work on the circuit protected by our interrupter and insure an open circuit for safety purposes.

From the foregoing it should be apparent that we have provided a circuit breaker of the type capable of automatically reclosing a circuit following an interrupting operation, which is operable to reclose the circuit a predetermined number of times and lock the breaker contacts open upon the occurrence of a permanent fault, and which will never lock the circuit breaker contacts open irrespective of the number of time spaced interruptions. Our novel breaker is also characterized by a novel arrangement of parts and simplified structure, so that a breaker of reduced size and which is economical in construction, is provided. Specifically, we have disclosed novel tripping means for a circuit breaker which

includes means to separate the breaker contacts sufficiently to draw an arc therebetween so that pressure developed by the arc in a substantially closed arc chamber operates to fully separate said contacts. Closing of the circuit breaker contacts is opposed by the novel time delay means disclosed, which is also responsive to a predetermined number of closely successive reclosures for locking the circuit breaker contacts in an open position. We have also disclosed certain specific features relating to a circuit breaker housing, and although all of these features have been particularly disclosed in a single unitary apparatus, it will be obvious to those skilled in the art that many of these features may be used independently, or in conjunction with other types of circuit breakers.

Having described preferred embodiments of our invention in accordance with the patent statutes, we desire that it be understood that our invention is not limited to the particular embodiments disclosed, since it will be obvious, particularly to persons skilled in the art, that many changes and modifications may be made in these specific structures without departing from the broad spirit and scope of our invention. Therefore, we desire that our invention be interpreted as broadly as possible and that it be limited only by what is expressly stated in the following claims and by the prior art.

We claim as our invention:

1. In a circuit interrupter, separable contacts mounted in a normally closed arc chamber with one of said contacts slidably mounted in a wall of said chamber for movement into and out of engagement with respect to the other of said contacts, normally closed vent means for said chamber, said vent means adapted to be opened in response to movement of said movable contact to substantially its fully opened position, and a check valve controlling a chamber inlet for permitting fluid flow into said chamber in response to a reduction in pressure therein.

2. In a circuit interrupter, separable contacts mounted in a normally closed arc chamber with one of said contacts slidably mounted in a wall of said chamber for movement into and out of engagement with respect to the other of said contacts, said one contact having a vent passage therethrough, the outer end of which is located so as to be positioned outside of said chamber only when said movable contact is separated a predetermined distance from the other of said contacts, and inlet means for said chamber normally closed at least during a circuit interrupting operation and adapted to open at least following a circuit interrupting operation to permit flushing of said chamber.

3. A circuit breaker including a container adapted to be substantially filled with an arc-extinguishing fluid, a substantially closed arc chamber therein, separable contacts in said chamber, vent means for an upper portion of said chamber adapted to be opened in response to a predetermined separation of said contacts, and a lower opening for said chamber controlled by a check valve for permitting fluid flow solely inwardly with respect to said chamber.

4. In a circuit breaker, a movable contact rod, tubular means having a cylinder portion about said rod, piston means movably mounted in said cylinder means, and a pawl and ratchet connection between said rod and piston means operative to connect said rod and piston means for movement together upon movement of said rod in a

direction to close the circuit through said breaker.

5. In a circuit breaker, a movable contact rod, tubular means having a cylinder portion about said rod, piston means in said cylinder portion, said means being mounted for relative movement, and means connecting said rod and one of said first two-mentioned means for movement with said rod when said rod moves in a direction to close the electrical circuit through said breaker.

6. In a circuit breaker, a movable contact rod, tubular means having a cylinder portion about said rod, piston means movably mounted in said cylinder means, and a pawl and ratchet connection between said rod and piston means operative to connect said rod and piston means for movement together upon movement of said rod in a direction to close the circuit through said breaker, and means normally biasing said piston means for movement in the opposite direction.

7. In a circuit breaker, a movable contact rod, tubular means having a cylinder portion about said rod, piston means in said cylinder portion, said means being mounted for relative movement, pawl and ratchet means connecting said rod and one of said first two-mentioned means for movement with said rod when said rod moves in a direction to close the electrical circuit through said breaker, and stop means for said one means positioned beyond the path of movement of said one means with said rod on the first closing movement thereof in any series of closely successive reclosures, whereby to maintain said rod in open circuit position in response to a predetermined number of closely successive circuit closing operations thereof.

8. In a circuit breaker, a movable contact rod, tubular means having a cylinder portion about said rod, piston means movably mounted in said cylinder means, a pawl and ratchet connection between said rod and piston means operative to connect said rod and piston means for movement together upon movement of said rod in a direction to close the circuit through said breaker, means normally biasing said piston means for movement in the opposite direction, and stop means for said piston means positioned to be engaged thereby to maintain said contact rod in open circuit position in response to a predetermined number of closely successive circuit closing operations thereof.

9. In a circuit breaker, a movable contact rod tubular means having a cylinder portion about said rod, piston means in said cylinder portion said means being mounted for relative movement, means connecting said rod and one of said first two-mentioned means for movement with said rod when said rod moves in a direction to close the electrical circuit through said breaker, said tubular means including an arc chamber portion adjacent said cylinder portion and into which said contact rod extends, and contact means in said chamber for cooperation with said contact rod to control the electric circuit through said breaker.

10. In a circuit breaker, a movable contact rod, tubular means having a cylinder portion about said rod, piston means movably mounted in said cylinder means, and a pawl and ratchet connection between said rod and piston means operative to connect said rod and piston means for movement together upon movement of said rod in a direction to close the circuit through said breaker, said contact rod having a slotted portion for mounting one element of said pawl and ratchet connection.

11. In a circuit breaker, a movable contact rod, tubular means having a cylinder portion about said rod, piston means movably mounted in said cylinder means, a pawl and ratchet connection between said rod and piston means operative to connect said rod and piston means for movement together upon movement of said rod in a direction to close the circuit through said breaker, said contact rod being hollow and having a slotted wall portion for mounting an element of said pawl and ratchet connection therein, said tubular means including an arc chamber portion adjacent said cylinder portion and into which said contact rod extends, contact means in said chamber for cooperation with said contact rod to control the electric circuit through said breaker, vent passage means through the wall of said hollow contact rod and positioned to be located outside said arc chamber only after predetermined separation of said contact rod and contact means, and partition means in said hollow contact rod between said slotted portion and said vent passage means.

12. In a circuit interrupter, a container adapted to be substantially filled with an arc-extinguishing liquid, tubular means in said container including an arc chamber portion having separable contacts therein, and a portion housing fluid time delay means operable to retard closing movement of said contacts, means flushing said arc chamber portion in response to separation of said contacts to interrupt the circuit, and said time delay means having intake means below the level of said liquid whereby to positively insure flushing of said chamber portion irrespective of the viscosity of said liquid.

13. In a circuit breaker unit, tubular supporting means including an arc chamber portion, and an adjacent housing portion, closure means for said arc chamber portion including a fixed partition between said housing and chamber portions, separable contacts in said chamber portion, and time delay means in said housing portion for delaying closure of said contacts a predetermined time after an interrupting operation thereof.

14. In a circuit breaker unit, tubular supporting means including a substantially closed arc chamber portion, and an adjacent housing portion, separable contacts in said chamber portion, and time delay means in said housing portion for delaying closure of said contacts a predetermined time after an interrupting operation thereof, supporting means extending from said tubular means for at least partly supporting electro-responsive means to separate said contacts sufficiently to draw an arc therebetween, at least one of said contacts being movable and having a part extending through a wall of said chamber whereby the pressure generated by said arc will further separate said contacts, and means normally biasing said contacts into engagement to automatically close said contacts when said arc is extinguished.

15. In a circuit breaker unit, tubular supporting means including a substantially closed arc chamber portion, and an adjacent housing portion, separable contacts in said chamber portion, time delay means in said housing portion for delaying closure of said contacts a predetermined time after an interrupting operation thereof, supporting means extending from said tubular means for at least partly supporting electro-responsive means to separate said contacts sufficient to draw an arc therebetween,

said electro-responsive means including an actuating member movably mounted on said supporting means and biased for movement in a direction to separate said contacts, and an element normally opposing said movement of said actuating member, but movable in response to predetermined electrical conditions of the circuit to release said actuating member.

16. In a circuit breaker, an interrupter unit comprising tubular supporting means including a substantially closed arc chamber portion, and an adjacent housing portion, separable contacts in said chamber portion, time delay means in said housing portion for delaying closure of said contacts a predetermined time after an interrupting operation thereof, supporting means extending from said tubular means for at least partly supporting electro-responsive means to separate said contacts, an insulating container for said unit, a cover for said container and to which said supporting means is connected to operatively support said unit in said container from said cover.

17. In a circuit breaker, an interrupter unit comprising tubular supporting means including a substantially closed arc chamber portion, and an adjacent housing portion, separable contacts in said chamber portion, time delay means in said housing portion for delaying closure of said contacts a predetermined time after an interrupting operation thereof, supporting means extending from said tubular means for at least partly supporting electro-responsive means to separate said contacts, an insulating container for said unit, a cover for said container and to which said supporting means is connected to operatively support said unit in said container from said cover, and an operating member movably mounted on said cover and connected to at least one of said contacts and having an operating portion extending to the outer side of said cover.

18. In a circuit breaker, a substantially closed arc chamber, separable contacts therein, one of which extends through a wall of said chamber and the other being substantially fixed in said chamber, means mounting said chamber and said one contact for relative movement, an actuating member biased for movement in one direction to separate said contacts sufficiently to draw an arc therebetween, said member having a lost motion connection to one of said contacts whereby the arc pressure in said chamber is operable to further separate said contacts, and current responsive means normally maintaining said member against movement.

19. In a circuit breaker, a substantially closed arc chamber, separable contacts therein, one of which movably extends through a wall of said chamber and the other being substantially fixed in said chamber, an actuating lever biased for movement in one direction to separate said contacts sufficiently to draw an arc therebetween, said lever having a portion adapted to contact an operating part operatively secured to said one contact to move the same out of engagement with the other of said contacts whereby said one contact is free to move further to increase the gap between said contacts by the pressure developed by said arc, and current responsive means normally preventing movement of said lever in said one direction.

20. In a circuit breaker, a substantially closed arc chamber, separable contacts therein, one of which movably extends through a wall of said

chamber and the other being substantially fixed in said chamber, an actuating lever biased for movement in one direction to separate said contacts sufficiently to draw an arc therebetween, said lever having a portion adapted to contact an operating part operatively secured to said one contact to move the same out of engagement with the other of said contacts whereby said one contact is free to move further to increase the gap between said contacts by the pressure developed by said arc, and current responsive means normally preventing movement of said lever in said one direction, said lever including a cam portion adapted to be engaged by said operating part upon said further movement of said one contact to reset said lever in a position to be reengaged by said current responsive means.

21. In a circuit breaker, a substantially closed arc chamber, separable contacts therein, one of which movably extends through a wall of said chamber and the other being substantially fixed in said chamber, an actuating lever biased for movement in one direction to separate said contacts sufficiently to draw an arc therebetween, said lever having a portion adapted to contact an operating part operatively secured to said one contact to move the same out of engagement with the other of said contacts whereby said one contact is free to move further to increase the gap between said contacts by the pressure developed by said arc, current responsive means normally preventing movement of said lever in said one direction, said lever including an inner cam portion adapted to be engaged by said operating part upon said further movement of said one contact to reset said lever in a position to be reengaged by said current responsive means, and an outer substantially straight portion on said lever engageable by said operating part adjacent the end of its opening movement to maintain said lever in a position to be reengaged by said current responsive means a predetermined time,

22. In a circuit interrupter, a container adapted to be substantially filled with an arc-extinguishing liquid, interrupting means in said container and including separable contacts submerged in said liquid, means for moving one of said contacts out of engagement with the other of said contacts, bimetal latch means controlling said contact moving means in response to predetermined current conditions, and normally positioned above the level of the liquid in said container, and means responsive to an interrupting operation of said interrupter for subjecting said bimetal means to said liquid to shorten the normal cooling time thereof.

23. In a circuit interrupter, a container adapted to be substantially filled with an arc-extinguishing liquid, interrupting means in said container and including separable contacts submerged in said liquid, means for moving one of said contacts out of engagement with the other of said contacts, thermal latch means controlling said contact moving means in response to predetermined current conditions, and normally positioned above the level of the liquid in said container, and means responsive to an interrupting operation of said interrupter for subjecting said thermal means to said liquid to shorten the normal cooling time thereof.

24. In a circuit interrupter, separable contacts mounted in a normally closed arc chamber adapted to be filled with an arc-extinguishing fluid, means for moving said contacts into and out of engagement, normally closed vent means

for said chamber adapted to open in response to predetermined separation of said contacts, an inlet opening for said chamber, and check valve means controlling said inlet opening to permit fresh fluid to flow into said chamber to replace used fluid which escapes from said vent.

25. In a circuit interrupter, fixed and movable contact means, means biasing said movable contact means into engagement with said fixed contact means, electroresponsive means for causing separation of said movable contact means from said fixed contact means a distance at least sufficient to draw an arc, and means utilizing the pressure developed by said arc to increase the separation of said contacts and extinguish the arc, whereby said contact means are automatically reclosed by said biasing means.

26. In a circuit interrupter, fixed and movable contact means, means biasing said movable contact means into engagement with said fixed contact means, time delay means opposing movement of said movable contact means by said biasing means, electroresponsive means for causing separation of said movable contact means from said fixed contact means a distance at least sufficient to draw an arc, and means utilizing the pressure developed by said arc to increase the separation of said contacts and extinguish the arc, whereby said contact means are automatically reclosed by said biasing means a predetermined time after a circuit-interrupting operation.

27. In a circuit interrupter, fixed and movable contact means, means biasing said movable contact means into engagement with said fixed contact means, time delay means opposing movement of said movable contact means by said biasing means, electroresponsive means for causing separation of said movable contact means from said fixed contact means a distance at least sufficient to draw an arc, means utilizing the pressure developed by said arc to increase the separation of said contacts and extinguish the arc, whereby said contact means are automatically reclosed by said biasing means a predetermined time after a circuit-interrupting operation, and means associated with said time delay means for preventing movement of said movable contact means into engagement with said fixed contact means in response to a predetermined number of successive reclosures thereof.

28. In a circuit interrupter, an arc chamber which is closed at least during a circuit-interrupting operation, separable contacts mounted in said chamber in a manner to be urged apart by any pressure developing in said chamber, electroresponsive means for separating said contacts and having a lost-motion connection therewith whereby the pressure generated by said arc in said chamber will be effective to further separate said contacts independent of said electroresponsive means.

29. In a circuit interrupter, an arc chamber which is closed at least during a circuit-interrupting operation, separable contacts in said chamber, one of which is slidably mounted through a wall of said chamber so as to be movable into and out of engagement with respect to the other of said contacts, electroresponsive means having a lost-motion connection with said movable contact to move said movable contact out of engagement with the other of said contacts in response to the occurrence of predetermined electrical conditions to strike an arc, whereby pressure developed by said arc in said

chamber is operable to cause further movement of said movable contact away from said other contact independent of said electroresponsive means.

5 30. In a circuit interrupter, an arc chamber which is closed at least during a circuit-interrupting operation, separable contacts mounted in said chamber in a manner to be urged apart by any pressure developing in said chamber, electroresponsive means for separating said contacts and having a lost-motion connection therewith whereby the pressure generated by said arc in said chamber will be effective to further separate said contacts independent of said electroresponsive means, and means biasing said contacts into engagement whereby the circuit will be automatically reclosed in response to extinction of said arc.

20 31. In a circuit interrupter, an arc chamber which is closed at least during a circuit-interrupting operation, separable contacts mounted in said chamber in a manner to be urged apart by any pressure developing in said chamber, electroresponsive means for separating said contacts and having a lost-motion connection therewith whereby the pressure generated by said arc in said chamber will be effective to further separate said contacts independent of said electroresponsive means, means biasing said contacts into engagement whereby the circuit will be automatically reclosed in response to extinction of said arc, and time delay means effective to delay reclosure of said contacts under the influence of said biasing means.

25 32. In a circuit breaker, a substantially closed arc chamber, separable contacts therein, one of which movably extends through a wall of said chamber and the other being substantially fixed in said chamber, an actuating lever biased for movement in one direction to separate said contacts sufficiently to draw an arc therebetween, said lever having a lost-motion connection with said one contact to move the same out of engagement with the other of said contacts whereby said one contact is free to move further to increase the gap between said contacts by the pressure developed by said arc, and current-responsive means normally preventing movement of said lever in said one direction.

30 33. In a circuit breaker, a substantially closed arc chamber, separable contacts therein, one of which movably extends through a wall of said chamber and the other being substantially fixed in said chamber, an actuating member biased for movement in one direction to separate said contacts sufficiently to draw an arc therebetween, said member having a lost-motion connection with said one contact to move the same out of engagement with the other of said contacts whereby said one contact is free to move further to increase the gap between said contacts by the pressure developed by said arc, and current-responsive means normally preventing movement of said member in said one direction.

35 34. In a circuit breaker, a substantially closed arc chamber, separable contacts therein, one of which movably extends through a wall of said chamber and the other being substantially fixed in said chamber, an actuating lever biased for movement in one direction to separate said contacts sufficiently to draw an arc therebetween, said lever having a lost-motion connection with said one contact to move the same out of engagement with the other of said contacts where-

by said one contact is free to move further to increase the gap between said contacts by the pressure developed by said arc, and current-responsive means normally preventing movement of said lever in said one direction, said lever including a cam portion adapted to be engaged by said operating part upon said further movement of said one contact to reset said lever in a position to be reengaged by said current-responsive means.

35. In a circuit interrupter, separable contacts, electroresponsive means for separating said contacts to draw an arc and having a lost-motion connection therewith, and means responsive to said arc for further separating said contacts independent of said electroresponsive means to insure sufficient contact separation to extinguish the arc.

36. In a circuit interrupter, a casing, interrupting means in said casing including separable contacts biased into engagement, electroresponsive means for separating said contacts, and means responsive to a predetermined number of successive circuit-interrupting operations for maintaining said contacts separated; a cover for said casing, an operating member movably mounted on the outside of said cover and associated with said contacts so as to assume different positions at least when said contacts are in engagement and maintained separated, respectively, means on said cover for receiving and concealing said operating member in its position corresponding to the engaged position of said contacts, and said member in its other position projecting from said means so as to provide a readily visible indication of the maintained open position of said contacts.

37. In a circuit interrupter, a casing, interrupting means in said casing including separable contacts biased into engagement, electroresponsive means for separating said contacts, and means responsive to a predetermined number of successive circuit-interrupting operations for maintaining said contacts separated; a cover for said casing, an operating member movably mounted on the outside of said cover and associated with said contacts so as to assume different positions at least when said contacts are in engagement and maintained separated, respectively, sleet hood means pivotally mounted on said cover for receiving and concealing said operating member in its position corresponding to the engaged position of said contacts, and said member in its other position projecting from said hood means so as to provide a readily visible indication of the maintained open position of said contacts.

38. In a circuit interrupter, a casing, interrupting means in said casing including separable contacts biased into engagement, electroresponsive means for separating said contacts, and means responsive to a predetermined number of successive circuit-interrupting operations for maintaining said contacts separated; a cover for said casing, an operating member movably mounted on the outside of said cover and associated with said contacts so as to assume raised and depressed positions at least when said contacts are in engagement and maintained separated, respectively, and releasable locking means on said cover for releasably maintaining said operating member in its depressed position corresponding to said maintained separated position of said contacts.

39. In a circuit interrupter, a casing, inter-

rupting means in said casing including separable contacts biased into engagement, electroresponsive means for separating said contacts, and means responsive to a predetermined number of successive circuit-interrupting operations for maintaining said contacts separated; a cover for said casing, an operating member movably mounted on the outside of said cover and associated with said contacts so as to assume different positions at least when said contacts are in engagement and maintained separated, respectively, means on said cover for receiving and concealing said operating member in its position corresponding to the engaged position of said contacts, and said member in its other position projecting from said means so as to provide a readily visible indication of the maintained open position of said contacts, and releasable locking means on said cover for releasably maintaining said operating member in its projecting position.

40. In a circuit interrupter, separable contacts mounted in a normally closed arc chamber with one of said contacts slidably mounted in a wall of said chamber for movement into and out of engagement with respect to the other of said contacts, normally closed vent means for said chamber, said vent means adapted to be opened in response to each circuit interrupting operation of said contacts, and a check valve controlling a chamber inlet for permitting fluid flow into said chamber in response to a reduction in pressure therein.

41. A circuit breaker including a container adapted to be substantially filled with an arc-extinguishing liquid, a substantially closed arc chamber therein, separable contacts in said chamber, vent means for an upper portion of said chamber adapted to be opened in response to each circuit interrupting operation of said contacts, and a lower opening for said chamber controlled by a check valve for permitting liquid flow solely inwardly with respect to said chamber.

42. In a circuit interrupter, separable contacts mounted in a normally closed arc chamber adapted to be filled with an arc-extinguishing fluid, means for moving said contacts into and out of engagement, normally closed vent means for said chamber adapted to open in response to each circuit interrupting operation of said contacts, an inlet opening for said chamber, and check valve means controlling said inlet opening to permit fresh fluid to flow into said chamber to replace used fluid which escapes from said vent.

43. In a circuit interrupter, separable contacts mounted in a normally closed arc chamber with one of said contacts slidably mounted in a wall of said chamber for movement into and out of engagement with respect to the other of said contacts, means for separating said contacts to interrupt the circuit, means for automatically reclosing said contacts in response to a circuit interrupting operation, normally closed vent means for said chamber, said vent means adapted to be opened in response to each circuit interrupting operation thereof, a check valve controlling a chamber inlet for permitting fluid flow into said chamber in response to a reduction in pressure therein, and time delay means for retarding closing of said contacts to permit flushing of said chamber by flow of fresh fluid in said chamber inlet for replacement of contaminated fluid escaping from said vent means.

44. In a circuit breaker, a movable contact rod, tubular means having a cylinder portion about said rod, piston means movably mounted in said cylinder means, and means connecting said rod and piston means for movement together during at least part of the movement of said rod in one direction.

45. In a circuit breaker, a movable contact rod, tubular means having a cylinder portion about said rod, annular piston means movably mounted in said cylinder means, and slidale between said rod and cylinder portion, and means connecting said rod and piston for movement together during at least part of the movement of the said rod in one direction.

46. In a circuit breaker, a container for an arc extinguishing liquid, a movable contact rod in said container, tubular means having a dashpot cylinder portion about said rod below the liquid level in said container, dashpot piston means in said cylinder portion, said means being mounted for relative movement, and means connecting said rod and one of said first two-mentioned means for movement with said rod when said rod moves in a direction to close the electrical circuit through said breaker.

47. In a circuit interrupter, a container adapted to be substantially filled with an arc-extinguishing liquid, interrupting means in said container and including separable contacts submerged in said liquid, means for moving said contacts apart to interrupt the circuit, bimetal latch means controlling said contact moving means in response to predetermined current conditions, and normally positioned above the level of the liquid in said container, and means responsive to an interrupting operation of said interrupter for subjecting said bimetal means to said liquid to shorten the normal cooling time thereof.

48. In a circuit interrupter, a fluid container

- having an open end, a terminal cap for said end, a line terminal at the opposite end of said container having a portion extending through the container wall to the interior thereof, an interrupting assembly mounted on said cap including separable contacts, electro-responsive contact separating means and reclosing means for the contacts, so that all of said elements are removable from said container as a unit with said cap, said contacts and electro-responsive means connected in series between said cap and a projecting assembly terminal positioned to be adjacent said line terminal when said cap is secured in operative position with respect to said container, and resilient conducting means telescopically engaging a portion of said assembly terminal and stressed against said line terminal in said operative position of the parts relative to the container.
49. In a circuit interrupter, a fluid container having an open end, a terminal cap for said end, a line terminal at the opposite end of said container having a portion extending through the container wall to the interior thereof, an interrupting assembly mounted on said cap including separable contacts, electro-responsive contact separating means and reclosing means for the contacts, so that all of said elements are removable from said container as a unit with said cap, said contacts and electro-responsive means connected in series between said cap and a projecting assembly terminal positioned to be adjacent said line terminal when said cap is secured in operative position with respect to said container, and a coil conducting spring telescopically engaging a portion of said assembly terminal and stressed against said line terminal in said operative position of the parts relative to the container.
